UNITED STATES PATENT OFFICE.

CHARLES BREARLEY MOORE, OF EVANSTON, ILLINOIS, ASSIGNOR, BY MESNE ASSIGNMENTS, TO AMERICAN ARCH COMPANY, OF NEW YORK, N. Y., A CORPORATION OF NEW YORK.

LOCOMOTIVE-BOILER FURNACE.

1,118,567.

Specification of Letters Patent.

Patented Nov. 24, 1914.

Application filed September 23, 1908. Serial No. 454,350.

To all whom it may concern:

Be it known that I, CHARLES BREARLEY MOORE, a citizen of the United States, and resident of Evanston, Cook county, Illinois, 5 have invented a certain new, useful, and Improved Locomotive-Boiler Furnace, of which the following is a full, true, clear, and exact description, such as will enable others skilled in the art to which it appertains to 10 make and use the same.

My invention relates to improvements in locomotive boiler furnaces and has particular reference to improvements in arches and arch structures for locomotive fireboxes.

15 The object of my invention is to provide a simple, economical and efficient arch structure for locomotive fireboxes.

20 My invention consists generally in a locomotive boiler furnace of the construction and combination of parts hereinafter described and particularly pointed out in the appended claim.

25 The invention will be more readily understood by reference to the accompanying drawings forming a part of this specification and in which;

30 Figure 1 is a vertical, longitudinal section of a locomotive boiler furnace embodying my invention; Fig. 2 is a similar view illustrating a modification of the invention.

35 The chief office of an arch in a locomotive firebox is to prevent the direct flow of the firebox gases from the grate to the flues and by deflecting or diverting the gases to cause the thorough admixture thereof with the air which enters through the grate or otherwise.

40 A locomotive firebox, as shown in the drawings, comprises the side sheets, 2, a rear sheet, 3, a flue sheet, 4, and a crown sheet, 5. 6 represents the firebox grate; 7 the flues leading from the flue sheet, 4, and 8 the flue door. The principal members or elements of my novel arch or gas mixing partition, as illustrated in Fig. 1, are the transverse members, *a*. These are regularly 45 spaced apart in the firebox and extend from side to side thereof. I prefer that the elements, *a*, shall be of Z form in cross section. They are made of refractory material, such as fire clay, which is capable of withstanding

a high temperature of the firebox. It will be observed that tortuous passages or openings, *b*, are left between several vertically positioned members, *a*, and that at top and bottom the flanges, *a'*, form horizontal deflectors. The gases therefore, which would otherwise pass directly from the bed of fuel on the grate to the flue sheet are deflected, baffled or diverted by the numerous vertical and horizontal portions of the refractory members, *a*, and thus the body of gas is thoroughly admixed and with a sufficient supply of air, substantially perfect combustion is insured. The members, *a*, may spring or 55 arch from side to side of the furnace, or may be supported upon arch tubes, 9, as shown in the drawings. At the lower end of the arch I prefer to close the openings or passages by means of horizontal bricks or 60 slabs, *c*, laid upon the flanges of the members, *a*. This latter construction, if desired, may be extended to the top of the arch by connecting several members, *a*, by horizontal bricks or slabs, *c*—*c*, as illustrated in Fig. 2. 65 Where this construction is carried out, the arch is provided with an irregular undersurface and a plurality of gas mixing pockets, 70 *d*, which materially assist in preparing the firebox gases for final combustion. In using 75 an arch of the construction shown in Fig. 2, I prefer to add thereto one or more air heating and introducing sections, *e*. The sides of the firebox are provided with air tubes, which communicate with the channels of the 80 sections, *e*, and air thus admitted is heated 85 in such sections and is discharged downwardly through the openings, *e'*, in the bottoms thereof.

As various modifications of my invention 90 will readily suggest themselves to one skilled in the art, I do not confine the invention to the specific constructions herein shown and described.

Having thus described my invention, I 95 claim as new and desire to secure by Letters Patent:

A locomotive fire box having a flue sheet at its front end, in combination with a plurality of refractory members spaced in an 100 ascending step like form in the fire box from the lower portion of the flue sheet, said re-

refractory members being substantially vertical and having substantially horizontal extending portions, the said refractory members being adapted to deflect, baffle and thoroughly admix the gases rising from the fuel bed before they pass into the flues, substantially as described.

In testimony whereof, I have hereunto set my hand, this 19th day of September, 1908, in the presence of two subscribing witnesses. 10

CHARLES BREARLEY MOORE.

Witnesses:

CHARLES GILBERT HAWLEY,

JOHN R. LEFEVRE.
